UNITED STATES PATENT OFFICE

2,188,428

AUXILIARY BAG FOR VACUUM CLEANERS

Maud E. Evans, Detroit, Mich.

Application September 19, 1939, Serial No. 295,635

6 Claims. (Cl. 183—51)

This invention relates to vacuum sweepers and has particular reference to an auxiliary bag which may be readily attached to vacuum sweepers of any make or model.

5 Medical authorities who have studied the problem, report that many diseases are caused by people inhaling the dust and germs which have been picked up and blown into the air by the modern vacuum cleaners.

10 A close examination of the air discharged through the walls of the filter bag of almost any vacuum sweeper will disclose a surprisingly large amount of fine dust and dirt, and other deleterious elements. It must follow, therefore, that 15 germs are also carried through the walls of the bag into the air which is breathed.

It is, therefore, one of the objects of this invention to eliminate most of the resulting dust and to greatly improve the sanitary aspects of using 20 a vacuum sweeper.

25 It is an object of the invention to provide an auxiliary bag for vacuum cleaners, which is adapted to trap most of the fine dust particles which now escape from the conventional vacuum cleaner bag.

Another object of the invention is the provision 30 of a device of the character referred to, which is provided with a germicidal medium intended to render harmless the greater proportion of the dangerous germs and microbes picked up and blown into the air through the walls of the present vacuum cleaner bags.

Other objects and advantages of the invention 35 will become more apparent as the description proceeds, reference being made from time to time to the accompanying drawing forming part of this disclosure, in which drawing:

Fig. 1 is a view, with parts broken away and partly in section, showing one of my improved 40 auxiliary bags in position on a conventional vacuum cleaner.

Fig. 2 is a section taken substantially on the line 2—2 of Fig. 1.

Fig. 3 is a fragmentary perspective view of one 45 of the spacers used on my bag.

Fig. 4 is an enlarged fragmentary plan view of a strip from which the spacer, illustrated in Fig. 3, is made.

Fig. 5 is a plan view of one of the sheets of 50 material from which the bag is formed. This view shows the manner in which the sheet is perforated and treated with a tacky germicidal substance, and the position assumed by the separators when attached.

Fig. 6 is an end view of the sheet, illustrated in

Fig. 5, illustrating the manner in which the tacky surface of the sheet is covered to facilitate the handling of the sheet in transportation.

Fig. 7 is an end view of the sheet, illustrated in Fig. 5, with the separators in position. 5

Fig. 8 is a modified form of my device.

Fig. 9 is a sectional view taken substantially on the line 9—9 of Fig. 8.

Referring now more particularly to the drawing, it will be seen that in the embodiment herein disclosed (Fig. 1), I illustrate my auxiliary bag 12 in position on a conventional vacuum sweeper 13, the filter bag of which is indicated by the reference character 14. In this embodiment, the upper end of the bag 12 is secured in position by 10 means of the spring clip 16, which is part of the standard equipment of this particular make of sweeper. It will be understood, however, that the upper end of the bag may be closed by means of a tie string, such as is illustrated at 17, which 15 closes the lower end of the bag and secures it to the sweeper 13.

As illustrated in Fig. 1, I propose to entirely envelop the conventional sweeper bag 14, with my auxiliary bag 12. I do this so that I may trap 20 such dust particles and other substances as might be forced through the walls of the bag 14.

My auxiliary bag 12 is preferably made of a single sheet of material (Fig. 5) which may either be a porous fabric or paper, provided with a plurality of minute perforations 18, through which the air may be permitted to escape. The inner 25 surface of the bag 12 is coated with a tacky substance 19 throughout a substantial portion of its area, except at the top 20 and the bottom 21 30 where the closure elements engage. The tacky substance 19 has incorporated with it a germicidal agent which is intended to kill any germs 35 with which it comes in contact. The tacky and germicidal substances extend throughout the major part of the inner surface of the auxiliary bag, so that substantially all of the air which is blown through the inner bag 14 of the vacuum 40 cleaner comes in contact with the tacky and germicidal elements before it escapes from the bag 12; whereby, practically all of the dust particles, germs and other foreign particles are 45 caused to adhere to the inner surface of the auxiliary bag before the air escapes into the room where the sweeper is being used.

The sheet of material from which the bag is formed, is provided with an adhesive substance along the area indicated at 22, so that the sheet 50 may be rolled into a cylinder and secured as illustrated in Fig. 2. In order to prevent the tacky 55

substance on the inner surface of the bag 12 from coming in contact with the outer surface of the bag 14, I provide a plurality of separators 23. These separators are preferably made of comparatively stiff paper, scored as indicated at 24 in Fig. 4, so that they may be bent into the form illustrated in Fig. 3. These separators are then secured to the inner surface of the sheet comprising the bag 12 along the dotted lines 25 (Fig. 5). The flat surfaces of the separators 23 are held in position by means of the adhesive quality of the tacky substance 19.

In order to facilitate the handling and storing of the sheets, I prefer to treat the inner surface 15 of the sheets and then cover the inner surface with a plain piece of paper 12a (Fig. 6). In this manner the sheets may be shipped flat, and when ready to be assembled the sheet 12a may be removed from the treated sheet 12; whereupon 20 the sheet is then ready to have the separators attached and to be rolled into a cylinder, and attached to the sweeper as hereinabove described.

This auxiliary bag may be removed and destroyed when the tacky surface will no longer 25 accommodate any more dust particles.

In Fig. 8, I illustrate a modified form of my device, wherein I provide a bag having a double thickness. In this modification, the outer member 26 and the inner member 27 are perforated 30 as indicated at 28. In this embodiment the inner member 27 may be of a substantially more rigid material than the outer member 26. The member 27 is formed with flared ends as at 29, so that a space 30 is provided between the members. 35 The space 30 is then filled with a suitable filter material 31, which has been impregnated with a tacky germicidal substance suitable for the purposes hereinabove referred to. Although I have herein disclosed the preferred embodiment of 40 my invention, it will be understood that certain modifications may be made to accomplish the same results, all of which are intended to be within the scope of the appended claims.

Having described my invention, what I claim and desire to secure by Letters Patent is:

1. A cover for a vacuum sweeper filter bag, comprising a sheet of material having means for the escape of air therethrough, said sheet having an area treated with a tacky and germicidal substance, said area being provided with a plurality of spacers adapted to prevent the contact of the tacky substance with the filter bag, and said sheet having an adhesive substance along at least one 10 edge thereof.

2. A cover for a vacuum sweeper bag, comprising two or more sheets of material adapted to permit the passage of air therethrough, there being a filter material disposed between said 15 sheets, said filter material being impregnated with a tacky germicidal substance.

3. The device defined in claim 2, wherein the outer sheet is longer than the inner sheet or sheets, and the long ends of said outer sheet are 20 adapted to serve as closure elements for the cover.

4. A device of the character described, comprising an envelope arranged in cooperation with the filter bag of a vacuum sweeper, said envelope 25 consisting of one or more sheets of material being pervious to air throughout substantially the entire area, said sheet or sheets being adapted to hold a tacky germicidal substance throughout substantially all of the pervious area. 30

5. A device as defined in claim 4, there being means to prevent the tacky substance from coming in contact with said filter bag.

6. A cover for a vacuum sweeper filter bag comprising a sheet of material, perforated, and 35 treated with a tacky germicidal substance throughout substantially all of its inside area, there being spacers positioned on the inside of said sheet, adapted to cooperate with the said sheet and said filter bag to prevent the tacky germicidal substance from coming in contact 40 with the said filter bag.

MAUD E. EVANS.
